LIQUEFIED GAS DISPENSING SYSTEM

Loyd J. White, San Antonio, Tex., assignor to
 Southern Steel Company, San Antonio, Tex., a
 corporation of Texas

Application October 2, 1944, Serial No. 556,832

10 Claims. (Cl. 62-1)

1

This invention relates to liquefied petroleum gas dispensing systems for generating and delivering gas derived from commercial butane or mixtures of butane and propane. More particularly, the invention applies to two-stage liquid eduction systems wherein the liquefied gas is withdrawn in the liquid phase from an underground, pressure storage tank and passes through a first-stage pressure reducer where it is partially vaporized; thence, through a vaporizer to complete the vaporization of the residual liquid; and, thence, through a second-stage pressure reducer to a service pipe, as generally illustrated in my U. S. Patents Nos. 2,176,829 and 2,260,356, and in my copending application Ser. No. 237,113, filed October 28, 1938. The main object of the present invention is to provide a new type of vaporizer which is removably associated with the storage tank and utilizes heat derived from the fuel contents of the tank and from a supplemental, external heating medium, not only to insure complete vaporization of the residual liquid, but also to augment the supply of heat delivered to the liquid fuel in the tank. Another aim is to provide a new type of re-vaporizer or heat exchanger for liquid fuel condensate formed in the service line and associated with the vaporizer, also to absorb heat from the fuel contents of the tank and from the supplemental heating medium, the arrangement being such that both the vaporizing and re-vaporizing units are incorporated in a composite assembly.

Other aims and advantages of the invention will appear in the specification, when considered in connection with the accompanying drawing, in which:

Fig. 1 is a vertical sectional view of an underground system embodying the invention, parts being shown in elevation;

Fig. 2 is a sectional view taken on the line 2-2 of Fig. 1; and

Fig. 3 is a longitudinal sectional view of the heat exchanger shown in Fig. 1.

Referring particularly to the drawing, and to the type of underground liquefied dispensing system shown therein, it will be understood that this invention applies to two-stage liquid eduction systems of the general type disclosed in the aforesaid Patents Nos. 2,176,829 and 2,260,356, wherein commercial butane, which usually contains from 10% to 25% propane, is discharged, in the liquid phase, from a pressure storage tank 10 which is usually buried in the ground below the frost line to absorb heat from the surrounding earth. The boiling point of the mixture is well

below 32° F., depending upon the amount of propane contained therein. The vapor pressure in the tank above the level of the liquid is sufficient to discharge liquid from the bottom portion of the tank through an eduction tube 11. In this instance, the tank is shown as having a riser pipe 12 connected thereto which carries a combination fitting 13, through which the liquid is adapted to be charged into the tank and dispensed therefrom. One form of fitting, which forms no part of the present invention, is shown in the aforesaid Patent No. 2,176,829. The liquid discharged through the eduction tube 11 is delivered from the fitting through a depending nipple 14 to which is connected an ordinary pressure reducing regulator 15 by means of an ordinary coupling 16, as shown in the aforesaid patent. The riser pipe and the appurtenances connected thereto are shown as being arranged within a housing or casing 17 connected to the tank and extending above the level of the ground so that the fitting 13 is easily accessible.

The pressure of the liquid is reduced by the regulator valve to, say, five pounds, gauge. The vapor pressure existing in the tank may vary between twenty and forty pounds, depending upon the character of the fuel and temperature of the earth around the tank. A part of the liquid flashes into vapor as it passes through the regulator valve because the educted liquid contains sufficient sensible heat to vaporize some of it; while the residual liquid is delivered from the regulator valve in the form of tiny droplets admixed with the vapor. In this example, the mixture of vapor and residual liquid is delivered from the regulator through a pipe 18, shown as being connected at its lower end to a T fitting 19 having a branch vapor conduit 20 connected thereto and leading to a second-stage regulator 21, which reduces the pressure of the vapor to the desired service pressure of about six ounces and delivers the vapor to an outlet pipe 22 connected to a service line 23. The vapor, which was mixed with the residual liquid, passes upwardly through the vapor conduit 20; while the residual liquid is separated therefrom in the T fitting 19 and is drained downwardly into and through a pipe 24 adjacent to the top wall of the tank and leading toward one end, as clearly shown in Fig. 1.

In accordance with this invention, the residual liquid delivered to the pipe 24 between the two regulators, is vaporized by absorbing heat not only from the contents of the tank but also from an external heating medium, to insure complete vaporization and to enable the system to carry a

heavy load. The pipe 24 is shown as being bent around the end head 25 of the tank and extending downwardly to a point where it is connected to a vaporizing chamber, shown as being in the form of a half cylinder 26 arranged within a cylindrical casing 27 extending horizontally through the head 25 into the bottom portion of the tank 10, so that it can absorb heat from the liquid fuel in the tank. The casing 27 may be, and preferably is, in the form of a large pipe closed at its inner end, so that the liquid in the tank cannot come into direct contact with the walls of the vaporizer 26. As clearly shown in Fig. 1, the pipe or casing 27 is preferably welded to the head 25. The vaporizer chamber 26 is shown as having an upstanding nipple 28 to which the pipe 24 is removably connected, the arrangement being such that the vaporizer can be removed through the open end of the casing. The casing 27 is shown as having a slot 29 through which the nipple projects to permit removal of the vaporizer chamber.

The vaporizer chamber is arranged to absorb heat delivered from the fuel contents of the tank through the casing 27. To supplement the supply of heat for vaporizing the residual liquid, and to increase the vaporizing capacity of the system, there is shown a separate liquid heat exchanger through which a liquid heating medium is circulated to deliver its heat to the vaporizer compartment 26. In this example, a semi-cylindrical compartment 30 is inserted in the bottom portion of the casing 27 and is connected to an inlet nipple 31 of a water service pipe. A longitudinal baffle 32, shown as extending to a point near the inner end of the compartment, is spot-welded in the central portion thereof to insure circulation of the water inwardly through the left hand side, as shown in Fig. 2, and outwardly through the right hand side to an outlet nipple 33 leading to the house. These nipples are, likewise, arranged in slots provided in the casing 27, so that the compartment 30 can be removed. The arrangement of the liquid heat exchanger in the bottom of the casing facilitates heat transfer upwardly to the vaporizing compartment 26, due to the natural tendency of the heat to rise therein. It will be understood that some of the contained heat in the circulating liquid will also be delivered to the contents of the tank and thereby increase the temperature of the fuel and thus increase the vaporizing capacity of the system. The arrangement of the separate liquid heating medium compartment in the casing, out of direct contact with the high pressure liquid fuel, insures safety in operation because it eliminates the danger of fuel entering a ruptured compartment or pipe and mixing with the liquid heating medium, which might cause an explosion when ignited.

It will be understood that the residual liquid between the two regulators flows downwardly through the pipe 24 along its bottom wall and the vapor returns from the vaporizer through the same pipe. It is then delivered with the separated, flashed vapor, through the pipe 20 and the second-stage or vapor regulator to the service pipe 23.

In this example, a re-vaporizer is also associated with the vaporizer 26. The service line 23 is shown as extending upwardly from a point adjacent to one end of the tank to provide a low point in the line to which liquid condensate will drain. At this point, there is shown a T fitting 34 in the service line, to which a depending pipe 35 is connected leading to a re-vaporizer,

shown as being in the form of a spur tube 36, extending into the vaporizing compartment 26 and having an upstanding nipple 37 adjacent to the nipple 28. The re-vaporizer requires much less heat than the vaporizer, because only a small quantity of condensate, formed when the system is overloaded or during extremely cold weather, is required to be re-vaporized and it is at a much lower pressure than the pressure existing in the vaporizer. It absorbs its heat from the residual liquid and vapor in the vaporizer. The condensate will be re-vaporized quickly and the vapor returned to the service line through the depending pipe 35 without conflicting with the draining condensate.

The vaporizer and re-vaporizer, together with the liquid heat exchanger, can be, and preferably are, assembled in a system before it is transported to the place of installation. In fact, the whole system is preferably assembled as a complete unit and the pipes, which are arranged adjacent to the tank, will not interfere with transportation. The open end of the casing 27 is shown as being closed by a sheet metal protecting cover or cap 38, telescoped over the outer end of the casing, which extends beyond the upstanding pipe nipples or connections. This prevents dirt or mud from entering the casing around the compartments and thus facilitates removal of the compartments for repairs or replacements.

From the foregoing description, it will be understood that the combination vaporizer and re-vaporizer, arranged to absorb heat from the fuel contents of the tank, as well as from an external source, greatly increase the capacity and efficiency of a two-stage liquid evaporation system. The parts are all easily accessible from the outside of the tank, where they can be removed for inspection and repairs. The semi-cylindrical compartments may be made by splitting a piece of standard pipe and welding flat walls on the split parts.

Having thus described the invention, what is claimed is:

1. In combination with a liquefied petroleum gas generating and dispensing system of the type wherein liquid fuel is delivered from the bottom of the tank through a first-stage pressure reducing regulator and partially vaporized, a heat exchanging casing projecting into the bottom portion of the tank and submerged in the liquid fuel; a vaporizer for the residual liquid delivered from the first-stage pressure reducing regulator removably mounted in said casing; conduit means connected to deliver the residual liquid to said vaporizer and return the vapor therefrom; and a second-stage pressure reducing regulator communicating with said conduit means and through which the vapor from the first-stage regulator and the vapor generated in said vaporizer are delivered; and a service pipe connected to the second-stage regulator.

2. In combination with a liquefied petroleum gas generating and dispensing system of the type wherein liquid fuel is delivered from the bottom of the tank through a first-stage pressure reducing regulator and partially vaporized, a heat exchanging casing projecting into the bottom portion of the tank and submerged in the liquid fuel; a vaporizer for the residual liquid delivered from the first-stage regulator removably mounted in said casing; a pipe connecting the first-stage regulator to deliver the residual liquid to said vaporizer and return the vapor therefrom; a supplemental heat exchanger also arranged in

said casing utilizing a circulating liquid as a heating medium for transferring vaporizing heat to the residual liquid; a second-stage pressure reducing regulator connected to said pipe and through which the vapor is delivered at service pressure; and a service pipe connected to the second-stage regulator.

3. In combination with a liquefied petroleum gas generating and dispensing system of the type wherein liquid fuel is delivered from the bottom of the tank through a first-stage pressure reducing regulator and partially vaporized, a heat exchanging casing projecting into the bottom portion of the tank and submerged in the liquid fuel; a vaporizer for the residual liquid delivered from the first-stage regulator removably mounted in said casing; a pipe connecting the first-stage regulator to said vaporizer to deliver the residual liquid and return the generated gas; a supplemental heat exchanger also arranged in said casing utilizing a circulating liquid as a heating medium for transferring vaporizing heat to the residual liquid; a second-stage pressure reducing regulator connected to said pipe through which the vapor is delivered at service pressure; a service pipe connected to the second-stage regulator and having a low point adjacent to the tank; a depending condensate drain pipe connected to the service pipe; and a re-vaporizer for the condensate also arranged within said casing adjacent to the vaporizer and connected to said drain pipe.

4. In a liquefied petroleum gas generating and dispensing system of the liquid eduction type wherein the liquid is delivered from a pressure storage tank through a first-stage pressure reducing regulator and the generated gas passes through a second-stage pressure reducing regulator to a service pipe, heat exchanging means between the regulators comprising a casing extending into the tank below the liquid level and having an open end outside the tank; an elongated vaporizer removably mounted in said casing connected to receive residual liquid delivered from the first-stage regulator and to deliver generated gas through the second-stage regulator; and an additional heat exchanger employing a circulating liquid as the heating medium also removably mounted in said casing to deliver supplemental heat to the vaporizer.

5. In a liquefied petroleum gas generating and dispensing system of the liquid eduction type wherein the liquid is delivered from a pressure storage tank through a first-stage pressure reducing regulator and the generated gas passes through a second-stage pressure reducing regulator to a service pipe, heat exchanging means between the regulators comprising a casing extending into the tank below the liquid level and having an open end outside the tank; an elongated vaporizer removably mounted in said casing connected to receive residual liquid delivered from the first-stage regulator and to deliver generated gas through the second-stage regulator; a re-vaporizer connected to receive condensate from a low point in the gas service pipe also removably mounted in said casing and associated with the vaporizer; and an additional heat exchanger in the casing employing circulating water as a heating medium to supply supplemental heat to the vaporizer and re-vaporizer.

6. In a liquefied petroleum gas generating and dispensing system of the liquid eduction type wherein the liquid is delivered from a pressure storage tank through a first-stage pressure re-

ducing regulator and the generated gas passes through a second-stage pressure reducing regulator to a service pipe, heat exchanging means between the regulators comprising a casing in the form of a large pipe extending into the tank below the liquid level and having an open end extending outside the tank, a vaporizer in the form of a portion of a cylinder inserted in said pipe and connected to receive residual liquid delivered from the first stage regulator and to deliver generated gas through the second-stage regulator; a re-vaporizer, in the form of a spurtube in the vaporizer, connected to receive condensate drained from a low point in the gas service line and to return vapor thereto; a supplemental heat exchanger, likewise in the form of a portion of a cylinder, inserted in the bottom portion of said pipe in heat exchanging contact with the vaporizer compartment; water inlet and outlet pipes connected to the outer end of the supplemental heat exchanger; and a longitudinal baffle between the water inlet and outlet connections to cause the water to circulate back and forth throughout the length of the supplemental heat exchanger.

7. In a liquefied petroleum gas generating and dispensing system, as set forth in claim 6, wherein the compartments constituting the vaporizer, and the water heat exchanging compartments are semi-cylindrical, complementary and substantially fill the large pipe, being removably mounted therein; and wherein a closure cap is mounted on the outside open end of said large pipe.

8. In a liquefied petroleum gas generating and dispensing system wherein fluid is delivered from a pressure storage tank through a first-stage pressure reducing regulator and fluid of reduced pressure then passes through a second-stage pressure reducing regulator to a service pipe, heat exchanging means between the regulators comprising an elongated casing extending into the tank below the liquid level and having an open end outside the tank; a first means in said casing connected to receive residual liquid delivered from the first stage regulator and to deliver generated gas through the second-stage regulator; and a second means connected to receive condensate from a low point in the gas service pipe also mounted in said casing and associated with said first mentioned means to deliver re-vaporized gas to the service pipe.

9. Apparatus, as set forth in claim 8, wherein said first and second means comprise a vaporizer and a re-vaporizer both removably mounted in said elongated casing.

10. In a liquefied petroleum gas generating and dispensing system wherein fluid is delivered from a pressure storage tank through a first-stage pressure reducing regulator and fluid of reduced pressure then passes through a second-stage pressure reducing regulator to a service pipe, heat exchanging means between the regulators comprising an elongated casing extending into the tank below the liquid level and having an open end outside the tank; a first means in said casing connected to receive residual liquid delivered from the first-stage regulator and to deliver generated gas through the second-stage regulator; a second means connected to receive condensate from a low point in the gas service pipe also mounted in said casing and associated with said first mentioned means; and an additional heat exchanger in the casing employing a circulating medium as a source of heat to supply supple-

mental heat to said first and second mentioned
means.
